FIG. 1.

THORVALD J. PETERSEN
INVENTOR

BY *Edwin Lewis*

ATTORNEY

UNITED STATES PATENT OFFICE.

THORVALD J. PETERSEN, OF NEW YORK, N. Y., ASSIGNOR TO GLOBE LIGHTING FIXTURE MFG. CO., OF BROOKLYN, NEW YORK.

DESIGN FOR A CHANDELIER OR ARTICLE OF SIMILAR NATURE.

Application filed May 11, 1927. Serial No. 21,934. Term of patent 3½ years.

To all whom it may concern:

Be it known that I, THORVALD J. PETERSEN, a citizen of the United States, residing at New York, in the county and State of New York, have invented a new, original, and ornamental Design for a Chandelier or Article of Similar Nature, of which the following is a specification, reference being had to the accompanying drawing, forming a part thereof.

Figure 1 is a perspective view of a chandelier showing my new design.

Figure 2 is a side elevational view showing in detail a component feature of the complete design illustrated in Figure 1.

I claim:

The ornamental design for a chandelier or article of similar nature as shown.

In testimony whereof I affix my signature.

THORVALD J. PETERSEN.
